UNITED STATES PATENT OFFICE

97,870

DESIGN FOR AN ENSEMBLE DRESS

Emil Schwartz, New York, N. Y.

Application November 13, 1935, Serial No. 59,515

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The circular elements on the sleeves and front panel portion of the jacket, and on the front and back of the dress, represent embroidered dots.

The rectangular structures at the back of the neck portion of the dress, as shown in Figure 4, represent cut-out areas.

I claim:

The ornamental design for an ensemble dress, substantially as shown and described.

EMIL SCHWARTZ.
